DESIGN FOR A RAKE HEAD

Andrew Jackson Johnson, Muncie, Ind.

Application February 4, 1943, Serial No. 109,459

Term of patent 14 years

To all whom it may concern:

Be it known that I, Andrew Jackson Johnson, a citizen of the United States, residing at Muncie, in the county of Delaware and State of Indiana, have invented a new, original, and ornamental Design for a Rake Head, of which the following is a specification, reference being had to the accompanying drawing, forming part thereof.

Figure 1 is a top plan view of the rake head showing my new design.

Figure 2 is a side elevational view looking at the inside of the rake teeth.

Figure 3 is an end elevational view.

I claim:

The ornamental design for a rake head, as shown.

ANDREW JACKSON JOHNSON.
